UNITED STATES PATENT OFFICE.

SAMUEL FENTON ALLEN, OF CHICAGO, ILLINOIS.

ANIMAL-SHEARS.

SPECIFICATION forming part of Letters Patent No. 642,831, dated February 6, 1900.

Application filed April 27, 1899. Serial No. 714,737. (No model.)

To all whom it may concern:

Be it known that I, SAMUEL FENTON ALLEN, of Chicago, in the county of Cook, State of Illinois, have invented certain new and useful 5 Improvements in Animal-Shears, of which the following is a complete specification, reference being had to the accompanying drawings.

The object of my invention is to produce 10 certain improvements in the construction of animal-shears whereby the facility of operation and the efficiency and durability of the machine are materially augmented.

In the accompanying drawings, Figure I is 15 a central longitudinal vertical section taken in a plane parallel to that in which the comb of the cutter is located, certain of the parts being shown in elevation. Fig. II is a view similar to that shown in Fig. I, but taken at 20 right angles to the plane in which that view is taken.

Referring to the numerals on the drawings, 1 indicates the bottom plate of the main frame of my machine, which is completed at one end 25 by a comb-plate 2, projecting forwardly from a shoulder 3, and at the other end with a rearwardly-extending grasp or handle 4. The handle 4, being adapted to accommodate a movable part, is preferably provided with terminal internal flanges 5 and 7 and an intermediate internal flange 6. These several flanges are provided with coaxial bores adapted to receive and fit a sleeve 8, which, extending from the flange 5 through the flange 7, projects about one-third of its entire length beyond the latter. The sleeve 8 is provided at its opposite extremities, respectively, with terminal bearings, preferably bushings 9 and 10, each preferably having an external annular flange 11. The bushings revolvably support a shaft 14, that carries upon one end an eccentric head 15 and upon the other and preferably threaded end 16 a gear 17. The gear 17 works against a washer 18, that encircles the shaft 14 and, projecting into an internal annular recess 19 in a collar 20 upon the sleeve 8, serves to revolvably retain the collar in position upon the sleeve. The gear 17, being screwed to the threaded end 16 of 50 the shaft 14, acts not only as a gear, but also as a nut for assembling the parts specified in

the manner described. By the removal of the gear 17 the parts secured thereby may be readily disassembled.

The gear 17 is adapted to coöperate as a 55 crown-gear or at any angle from a right angle, as a beveled gear with a corresponding gear 21, carried, as upon a power-shaft 22, within a frame 23, that is hinged, as indicated at 24, to the collar 20. The hinges 24 permit relative swinging movement of the collar 20 and frame 23, while the revolvability of the collar 20 upon the sleeve 8 independent of the movement of the shaft 14 affords free movement of the frame of the machine about the axis 60 of the shaft 14 through manipulation of the handle 4.

The sleeve may be secured within the handle 4, as by a series of screws 25, screwing through threaded apertures in the handle 70 and flange 6 and engaging, as by abutment, with the wall of the sleeve 8. One of the series of screws 25, specially indicated by the reference numeral 26, is conically pointed and pierces the wall of the sleeve 8. This arrangement besides contributing to the security of union between the handle 4 and the sleeve 8 affords a suitably-closed oil-hole, through which a lubricant may be supplied to the oil-chamber 28, defined within the sleeve 8 between the opposite ends of the bushings 9 and 10. The chamber 28 is also partially occupied by the shaft 14, which when the chamber is filled with a lubricant revolves within it and has its bearings constantly supplied from this 85 abundant source.

The presence of a lubricant-chamber is an important feature in machines operated at so high a velocity as machines of this class are operated; but the important feature of my 90 invention in this respect is the location of the lubricant-chamber within the handle in such a manner as to practically prevent all leakage of the lubricant therefrom.

The plate 1 is preferably bounded upon opposite sides by side walls 30, which are preferably surmounted by a cap-plate 31. The cap-plate should constitute a rigid part of the machine, and for that purpose may be secured to the side walls 30, as well as to the inner face 100 of the handle 4, as by a plate consisting of a continuation of the plate 31, bent at right an-

gles thereto. The plate 31, besides affording in conjunction with the plate 1 and side pieces 30 a box for certain of the working parts of the machine, is designed to afford a support 5 for a vibrator-pin 34, that will render said pin relatively rigid and immovable with respect to the frame of the machine. The pin 34 may consist, essentially, of a headed bolt having a reduced threaded end 35, passing through 10 an aperture in the cap-plate 31 and secured in place by a nut 36, screwing on the threaded end 35. As its name suggests, it is designed to support the vibrator 37, and its mounting above described is designed to sustain the 15 great wear and strain to which the vibrator is in practice subjected. The vibrator is provided with a sleeve 38, that fits the pin 34, about which it oscillates. The sleeve 38, with the vibrator, extends from the face of the 20 plate 1 to the bottom of the cap-plate 31.

40 indicates a washer of suitable material, countersunk in the face of the plate 1 and which, surrounding the pin 34, supports the vibrator 37. The vibrator 37, as will appear 25 from a comparison of Figs. I and II, is essentially an oblong member projecting in opposite directions from the sleeve 38. It carries upon its rearward and curved jaws 41, between which works with a vertically-recipro- 30 catory and laterally-oscillatory movement a cylinder 42, that is supported upon an eccentric stud 43, projecting from the face of the eccentric head 15. The cylinder 42 is provided with a transverse aperture to receive 35 the stud 43. With said aperture communicates upon opposite sides flared or funnel-shaped recesses 44. One of these recesses in operation is designed to carry a quantity of lubricating material and feed it as required 40 to the stud 43. By the employment of the two recesses 44 the cylinder may be set in four different positions upon the stud, and thereby equally distribute the wear upon the bearing parts with which it co-operates.

45 Upon the end of the vibrator opposite the jaws 41 I provide a pair of lugs 45, between which, as upon a screw 46, is pivoted a tension-lever 47, that is provided with an apertured lug 48, fitting between the lugs 45 and 50 pierced by the screw 46. The tension-lever 47 is secured at its forward end, as by screws 50, to a cutter 51, that reciprocates across a comb 52, secured, as by screws 53, to the comb-plate 2. The rearwardly-extending end 55 of the tension-lever 47 is provided with a collar 54, having an elliptical or oblong aperture 55 encircling the sleeve 38. The longer diameter of the aperture 55 being disposed lengthwise of the tension-lever 47 permits a 60 limited movement of said lever upon its pivot-screw 46. The shorter diameter of the aperture 55 is such as to cause it to fit snugly upon the sleeve 38 and to assist the lugs 45 and 46 in rigidly securing the tension-lever 47 to 65 the vibrator 37.

Immediately in rear of the lugs 45 I provide

a plate or bridge 56, which, secured to the comb-plate 2, as by screws 57, serves to confine the vibrator snugly against the face of the comb-plate during its vibratory movements. Immediately in the rear of the bridge 56 I provide a tension-screw 58, screwing through a threaded aperture provided for it in the tension-lever 47 and abutting against the face of the vibrator 37. The movement 75 of the screw 58 serves to regulate, through the tension-lever 47, pressure of the cutter 51 against the comb 52. I prefer to have the screw 58 extend through an aperture 59 in the cap-plate 31 and to provide it, above the 80 cap-plate, with an enlarged head 60, notched, as indicated at 61, around its under side, said notches being adapted to engage with a spring plate or pawl 62, rising from the cap-plate 31, to which it is secured, as by screws 63. 85

The method of manipulating and adjusting the several parts above described has been incidentally pointed out in the specification, and the operation of the machine does not therefore appear to require to be further enlarged upon in this specification, addressed as it is to those skilled in the art to which this invention belongs.

What I claim is—

1. In a shearing-machine, the combination 95 with a frame comprising a hollow handle, of a sleeve within the handle, rotatory shaft carried in terminal bearings within the sleeve, a lubricant-chamber within the sleeve between said bearings, a screw-hole, and conical aperture through the handle and sleeve, respectively, and a conically-pointed screw working therein, substantially as and for the purpose specified.

2. In a shearing-machine, the combination 105 with a frame, rotatory shaft, head upon the shaft, and eccentric stud upon the head, a vibrator movably secured to the frame, jaws thereon in proximity to the head, and a cylinder bored to fit the stud and provided with 110 opposite funnel-shaped recesses communicating with the bore, substantially as and for the purpose specified.

3. In a shearing-machine, the combination 115 with a frame, rotatory shaft, head upon the shaft and eccentric stud upon the head, a vibrator movably secured to the frame, jaws thereon in proximity to the head, and a cylinder bored at right angles to its axis to fit the stud, and provided with opposite coaxial funnel-shaped recesses communicating with the bore, substantially as set forth.

4. In a shearing-machine, the combination 125 with a frame provided with side pieces and a cap-plate surmounting the side pieces, of a pin, rigidly and independently secured as to its opposite ends, in the frame and cap-plate respectively, a vibrator, movable upon said pin, and vibrator-actuating mechanism, substantially as set forth.

5. In a shearing-machine, the combination 130 with a frame, vibrator, and vibrator-actuating

mechanism, and a tension-lever fixedly fulcrumed, near its middle part, to the forward end of the vibrator, and an abutment screw-threaded to the tension-lever and abutting 5 against the vibrator, substantially as set forth.

6. In a shearing-machine, the combination with a frame, vibrator-pin, and vibrator provided with a sleeve upon said pin, of a tension-lever pivoted to the forward end of the vibrator provided with a collar having an oblong aperture encircling the sleeve of the vibrator, and an abutment screw-threaded to the tension-lever between its pivotal connection with the vibrator, and its collar, and abutting 10 against the vibrator, substantially as set forth.

7. In a shearing-machine, the combination with a frame, vibrator and pair of lugs upon the forward end of the vibrator, of a tension-lever provided with a lug fitting between the 15 lugs upon the vibrator, a pivot-screw uniting said lugs, an additional rearwardly-disposed connection between the tension-lever and the vibrator, and tension-regulating mechanism

carried on the tension-lever, and coöperating against the vibrator, substantially as set forth. 25

8. In a shearing-machine, the combination with a frame, vibrator-pin, and vibrator comprising a sleeve working upon said pin, of a tension-lever pivoted to the vibrator, a collar provided with an oblong aperture encircling 30 the sleeve of the vibrator, side pieces, and a cap-plate upon the frame surrounding the rearward end of the vibrator, a screw carried upon the tension-lever, abutting against the vibrator, and extended through an aperture 35 in the cap-plate, a head upon said screw, teeth upon said head, and a spring-plate secured to the frame, and detachably engaging said teeth, substantially as and for the purpose specified.

In testimony of all which I have hereunto 40 subscribed my name.

SAMUEL FENTON ALLEN.
